Rufus Tyler & Denton Boston

The Schedule referred to in these Letters Patent and making part of the same containing a description in the words of the said Rufus Tyler and Denton Boston themselves of their improvement in preparing Leghorn Straw, and other Hats.)

The machine for preparing Leghorn Straw, and other Hats, consists of a stand of convenient height and form, on the top of which is a cover having a fulcrum in a swivel, passing through the top of the stand. (or the fulcrum is a box or case (deeper than the breadth of the cover,) the top of which is open, the bottom faced with Steel, glass or other material, the case is for containing a block of iron which is heated (and imparts its heat to the bottom of the box or case) operable in the operation of preparing the hat. This block has a hole near the top, through which the bent end of a rod passes to lift it out of the case for the purpose of being heated. A rod, one end of which serves to hold the hat block in a horizontal position, passes through the front leg of the stand, having a crank at the other end, used in turning the hat block, and with it the hat, while the cover containing the case or box, is pressed down by the hand upon the side of the hat. The crown is prepared by slipping the hat block from the rod which turned it, and placing it on a bracket projected from the side of the stand. The hat block is then turned by hand, while the cover is pressed upon it. The brim is pressed on the broad part of the top of the stand.
